UNITED STATES PATENT OFFICE.

WILBER E. HUNTER, OF MORGANTOWN, WEST VIRGINIA.

DESIGN FOR A TUMBLER.

43,808.

Specification for Design.

Patented Apr. 1, 1913.

Application filed February 24, 1913. Serial No. 750,421. Term of patent 7 years.

To all whom it may concern:

Be it known that I, WILBER E. HUNTER, a citizen of the United States, residing at Morgantown, in the county of Monongalia and State of West Virginia, have invented a new, original, and ornamental Design for Tumblers, of which the following is a specification, reference being had to the accompanying drawing, forming a part thereof.

The figure is a perspective view of a tumbler, showing my new design.

I claim—

The ornamental design for a tumbler as shown.

WILBER E. HUNTER.
